Filed Mar. 19, 1970, Ser. No. 21,967

Term of patent 14 years

Int. Cl. D6—01

U.S. Cl. D5—4

The single figure is a perspective view of a bunk bed, showing my new design, an opposite perspective view being substantially a mirror image thereof.

The patches of criss-crossed lines represent fragments of a mesh panel connected to the end and side rails of each individual bunk to form a continuous bunk bottom within the boundaries indicated.

I claim:

The ornamental design for a bunk bed, as shown and described.
